UNITED STATES PATENT OFFICE

2,417,922

MOUNTING MEANS FOR FABRIC AND LIKE
COVERING SHEETS

John E. Frazer, Burbank, Calif., assignor, by
mesne assignments, to Lockheed Aircraft Cor-
poration, a corporation of California

Application March 5, 1945, Serial No. 581,147

13 Claims. (Cl. 160—384)

1

This invention relates to and has for its primary object the provision of a mounting means for securing fabric coverings or linings to walls and other parts in the interior of aircraft cabins, railroad cars, boats, ships, automobiles, and the like, which means may be quickly and easily applied, will prove of pleasing and ornamental appearance and hide all seams and joints of the applied coverings or linings.

Another object of the invention is to provide a mounting means such as described which is of simple construction, economical to manufacture, may be readily and easily applied to flat, curved or irregular surfaces with equal efficacy and easily removed and repeatedly used.

A further object of this invention is to provide a mounting means such as described which includes a base strip and a cover strip, the former of which is adapted to be detachably secured in place and has means thereon for readily and detachably securing in place fabric or like sheets or pieces as coverings for walls, panels, seats and other objects in the interior of vehicle cabins, compartments, etc., or in the rooms of dwellings and on articles of furniture; the cover strip being constructed and arranged so that it may be quickly and easily detachably applied to conceal the base strip and joints or seams of the fabric sheets or like pieces, and having locking means thereon adapted to snap into interlocking engagement with the fabric holding means on the base strip to detachably secure the cover strip to the base strip.

With the foregoing objects in view, together with such other objects and advantages as may subsequently appear, the invention resides in the parts and in the combination, construction and arrangement of parts hereinafter described and claimed, and illustrated by way of example in the accompanying drawing, in which:

Fig. 1 is a fragmentary perspective view of the base strip of the mounting means of this invention;

Fig. 2 is a fragmentary perspective view of the cover strip made in accordance with this invention;

Fig. 3 is a fragmentary front elevation of the base strip as installed;

Fig. 4 is a cross sectional view of the mounting means showing the manner of applying the cover strip to the base strip;

Fig. 5 is a view similar to Fig. 4 showing the mounting means completely installed;

Fig. 6 is a fragmentary front elevation showing the completely installed mounting means;

2

Fig. 7 is a fragmentary perspective view of a modified form of base strip;

Fig. 8 is a sectional view of a modified form of cover strip;

Fig. 9 is a fragmentary perspective view of a modified form of base strip;

Fig. 10 is a sectional view of the base strip shown in Fig. 10 as applied to an inside corner, together with a modified form of cover or molding strip;

Fig. 11 is a fragmentary perspective view of another modified form of base strip;

Fig. 12 is a sectional view of the form of strip shown in Fig. 11 as applied to an outside corner, together with another modified form of cover or molding strip;

Fig. 13 is an enlarged fragmentary horizontal sectional view of the unit shown in Figs. 4 and 5 when used to hold a single cover sheet in place instead of the two sheets as shown in Figs. 4 and 5.

Referring more in detail to the drawings, it is seen that one embodiment of my invention includes a base strip 9 preferably made of thin, flexible and resilient sheet metal and having openings 10 therein for studs 11 or the like employed with push-on or other suitable nut-like fastenings 12 to detachably secure the strip to a wall or other member 13 in preparation for mounting sheets or pieces of fabric 14 in place. In having the base strip flexible and resilient it may be applied to curved or irregular surfaces as readily as to flat surfaces and will conform thereto without bulging or being distorted objectionably.

Means is provided on the base strip for detachably securing one or more of the fabric sheets or pieces 14 thereto and as here shown comprises a plurality of prongs 16 bent over from the side edges of the base strip and arranged in staggered relation to one another. The prongs are tapered to provide sharp pointed free ends facing inwardly so that the fabric pieces 14 may be hooked thereto with the prongs piercing the fabric and the edges of the fabric disposed in closely spaced relation and lying upon the base strip as shown in Figs. 3 and 4. It now is apparent that after the strip 9 has been secured to the wall or support 13, the fabric may be quickly and easily hooked onto the prongs 16 to make a flat and neat joint or seam, as shown in Figs. 3 and 4. However, if desired the fabric may be hooked to the base strip before such strip is secured in place.

In accordance with this invention an elongated cover strip 18 considerably wider than the

base strip and made of resilient flexible sheet metal or similar material is constructed and arranged to fit over and conceal the base strip 9 as well as the seam or joint of the fabric with the base strip and the portions of the fabric lying upon the base strip, there being a fastening means on the cover strip providing for a quick interlocking thereof with the fabric holding prongs 16 whereby the cover strip is securely but detachably held in place. As here shown this means includes rebent flanges 19 formed along the side edges of the normally flat body portion of the cover strip, such flanges extending inwardly and normally lying in spaced and substantially parallel relation to the body of the cover strip, the free longitudinal edge portions of the flanges 19 being back on themselves to form outwardly opening hook-like flanges or hook edges 20 extending the full length of the free longitudinal edges of the cover strip.

As shown in Fig. 2, to apply the cover strip one of the hook edges 20 thereof is hooked onto the row of prongs 16 along one edge of the base strip 9, and the cover strip is then flexed so that it will bow outwardly to the extent that the other hook edge 20 is brought to a position to hook onto the prongs 16 along the other edge of the base upon releasing the cover strip. This flexing of the cover strip may be effected by pressing inwardly on the rounded side edges 21 of such strip while one hook edge thereof is hooked onto the prongs 16 as shown in Fig. 4. When the other hook edge has been forced inwardly past the other row of prongs 16, the operator pushes inwardly on the cover strip then releases the pressure on the side edges thereof whereupon the inwardly sprung hook edge 20 will spring outwardly into hooked engagement with said other row of prongs 16 and become locked on the two rows of prongs under tension as shown in Figs. 5 and 6.

It should be noted that when the cover strip is in place as shown in Figs. 5 and 6, it will be bowed outwardly so as to present a transversely curved or convex outer surface with the curved outer edges 21 thereof lying against or close to the fabric pieces, thereby not only entirely concealing the base strip and seam or joint of the fabric pieces but providing a neat and smooth fixture which is of ornamental appearance.

To remove the cover strip it is only necessary to press against the sides to bring one of the hook edges 20 to the position shown in Fig. 4, free of the prongs 16 along one edge of the base strip, whereupon the other hook edge 20 may be readily disengaged from the other set of prongs.

A modified form of base strip shown in Fig. 7 includes a flat, flexible resilient metal base strip 22 identical with the strip 9 except that the prongs 23 are struck out from such strip at points adjacent the side edges of the latter, said prongs being arranged in the same staggered relation as are the prongs 16. The cover strip 18 is applicable to the strip 22 in the same manner as it is applied to the base strip 9.

Fig. 8 shows a modified form of cover strip 24 which is applicable alike to the base strips 9 and 22. This modified cover strip is made of resilient sheet material, for example, a springy plastic, and is of concavo-convex form having on its concave side a pair of integral and flexible ribs or flanges 25 which extend divergently therefrom for the full length of the strip and are adapted to extend under the prongs on the base strip 9 as shown in Fig. 8 or on the prongs 23 of base

strip 22 to lock the cover strip on the base strip. These ribs or flanges are disposed adjacent and on opposite sides of the longitudinal medial line of the cover strip 24. Upon flexing or bowing the strip 24 as by pressing in against opposite sides thereof, the flanges 25 are flexed toward one another and therefore this form of strip may be applied to and removed from either of the base strips here shown in the same manner as the cover strip shown in Fig. 2. It will cover the entire joint and the base strip will remain outwardly bowed with its convex side outermost. It may as here shown be of angular cross section and is normally bowed a lesser extent than when applied whereby it is held in place under spring tension with the flanges 25 exerting outward pressure against the prongs 23.

Another modified form of my invention, as shown in Figs. 9 and 10, includes an angle iron (right angular) form of base strip 27 for application to the right angular wall member 28 of an inside corner, as shown in Fig. 10, there being inwardly turned pointed prongs 29 onto which the fabric sheets 30 and 31 are hooked. This base strip is secured in place by suitable fastenings 32 and is covered by a cover or molding strip 33 similar to the one 24 shown in Fig. 8. The strip 33 is concavo-convex but has the flared attaching flanges 34 on its convex side so that when applied the concave side is outermost for a better fit in the corner. The prongs 16 are resilient and yieldable and the cover strip 33 is made of resilient metal or somewhat "springy" plastic or the like so that the flanges 34 are yieldable and may be forced past the likewise yieldable prongs 16 into interlocked engagement therewith, as shown in Fig. 10, to hold the cover strip in place effectively covering and concealing the base and the joints of the fabric therewith.

Figs. 11 and 12 illustrate another form of my invention wherein a base strip 36 of right angular form is provided with resilient prongs 37 on the "outside" thereof so that the base strip may be secured by fastenings 38 as shown in Fig. 12 to the wall member 39 on an "outside" corner. A modified form of cover strip 40 is shown applied to the base strip in Fig. 12 to cover the latter and the joints of the fabric sheets 41 and 42 hooked on the prongs 37. The cover strip 40 is substantially semi-circular and has attaching flanges 43 extending longitudinally of the concave surface thereof near the longitudinal edges of the strip, for interlocking engagement with the prongs 37. This cover strip is made of somewhat resilient or "springy" plastic or like material so that it may be sprung into interlocking engagement with the base, with its flanges 43 in tensioned contact with the resilient prongs 37. As this form of cover strip projects outwardly in rounded form from the inside corner it is relatively thick and rigid so that it will withstand being bumped against moving objects around or adjacent such an exposed corner, and will not be subject to being dislodged.

Fig. 13 shows the same form of my invention as illustrated in Figs. 4 and 5 but as applied to a wall structure 44 such that but one cover sheet 45 is secured by the base strip, as at a door or window frame. In this connection it should be noted that any of the forms here shown could be used to fasten one instead of two fabric sheets as desired.

A feature of advantage common to all forms of my invention is that the prongs for securing the fabric also serve to releasably hold the cover

strips in place concealing the base strips and joints of the fabric therewith.

It is now apparent that the mounting means embodying my invention may be quickly and easily applied with a saving in time, labor and material to provide a secure detachable mounting or joining means for fabric covering sheets and the like. The construction and arrangement of the means is such that it will hold the cover sheets tightly in place and will not loosen under vibrations while providing a flat, neat, decorative and rugged joint of light weight and subject to easy disassembly.

While I have shown and described specific embodiments of my invention I do not limit myself to the exact details of construction set forth, and the invention embraces such changes, modifications and equivalents of the parts and their formation and arrangement as come within the purview of the appended claims.

I claim:

1. In a mounting means for supporting a covering sheet of fabric, a base strip adapted to be mounted on the surface of an object to which such sheet is to be applied; fastening elements on said strip for supporting the sheet on said strip, a cover strip adapted to overlie and conceal said base strip, and hook formations on said cover strip interlocking with said fastening elements at points concealed by said cover strip to secure the latter to the base strip in position concealing said base strip and the joint of the sheet therewith.

2. In a mounting means for supporting a covering sheet of fabric, a base strip adapted to be mounted on the surface of an object to which such sheets are to be applied, fastening elements on said strip for engaging an edge of the sheet and holding it on said strip, a flexible resilient cover strip adapted to overlie and conceal said edge and said base strip, and hook formations on said cover strip for interlocking with said fastening elements at points concealed by said cover strip to secure the latter to the base strip in position concealing said edge of said sheet and the base strip.

3. In a mounting means for joining and supporting covering sheets of fabric, a base strip adapted to be mounted on the surface of an object to which such sheets are to be applied, fastening elements on said strip for joining edges of said sheets and holding them on said strip, a cover strip adapted to overlie and conceal said edges and said base strip, and hook formations on the longitudinal edges of said cover strip for interlocking with said fastening elements at points concealed by said cover strip to secure the latter to the base strip in position concealing said edges and the base strip.

4. In a mounting means for joining and supporting covering sheets of fabric, a base strip adapted to be mounted on the surface of an object to which such sheets are to be applied, fastening elements on said strip for joining edges of said sheets and holding them on said strip, a cover strip adapted to overlie and conceal said edges and said base strip, and hook formations integral therewith and lying on the inner face thereof at points spaced inwardly of the longitudinal edges of the cover strip and subject to being hooked onto said fastening elements to detachably secure the cover strip to said base strip.

5. In a mounting means for fastening in place a covering sheet of fabric, a base strip adapted to

be mounted on the surface of an object to which such a sheet is to be applied, fastening elements on said strip for engaging an edge of said sheet and holding it on said strip, a cover strip adapted to overlie and conceal said secured edge of the sheet and said base strip, and flanges on the inner side of said cover strip at points spaced inwardly of the side edges of the cover strip having hooked engagement with said fastening elements to secure the cover strip to the base strip.

6. In a mounting means for holding in place a covering sheet of fabric, a base strip adapted to be mounted on a structure to which such a sheet is to be applied, prongs formed on said strip overlying one face thereof and facing inwardly so that an edge portion of the covering sheet may be hooked thereto to overlie said strip, a cover strip of greater width than said base strip, and fastening means embodied in said cover strip on the inner side and inwardly spaced from the side edges thereof for interlocking engagement with said prongs to detachably secure the cover strip to the base strip.

7. In a mounting means for holding in place a covering sheet of fabric, a base strip adapted to be mounted on an object to which such a sheet is to be applied, prongs formed on said strip overlying one face thereof and facing inwardly so that an edge portion of the covering sheet may be hooked thereto to overlie said strip, a cover strip of greater width than said base strip, flanges extending inwardly from the side edges thereof and overlying the inner face of the cover strip, and hook formations on the free edges of said flanges adapted to hook under said prongs to hold the cover strip on the base strip.

8. In a mounting means for joining and supporting covering sheets of fabric, a base strip adapted to be mounted on an object to which such sheets are to be applied, prongs formed on said strip in rows adjacent longitudinal edges of the strip and overlying one face thereof and facing inwardly so that edge portions of the covering sheets may be hooked thereto to overlie said strip, a cover strip of greater width than said base strip, flanges extending inwardly from the side edges thereof and overlying the inner face of the cover strip, hook formations on the free edges of said flanges adapted to hook under said prongs to hold the cover strip on the base strip, said cover strip being flexible and resilient and said hook formation being disposed so that when the hook formation on one edge of one flange is hooked under one row of prongs, the other hook formation on the other edge may be forced into hooked engagement with the other row of prongs upon flexing said cover strip so that it bows outwardly between its side edges.

9. In a mounting means for supporting a covering sheet of fabric, a base strip adapted to be mounted on an object to which such a sheet is to be applied, fastening elements on said strip for supporting the sheet on said strip, a cover strip adapted to overlie and conceal said base strip, and hook formations on said cover strip for interlocking with said fastening elements at points concealed by said cover strip to secure the latter to the base strip in position concealing said base strip and the joint of the sheet therewith, said base strip being of right angular formation in cross section and adapted to be applied to a corner structure.

10. In a mounting means for holding in place a covering sheet of fabric, a base strip adapted to be mounted on a structure to which such a

sheet is to be applied, prongs formed on said strip overlying one face thereof and facing inwardly so that an edge portion of the covering sheet may be hooked thereto to overlie said strip, a cover strip of greater width than said base strip, and fastening means embodied in said cover strip on the inner side and inwardly spaced from the side edges thereof for interlocking engagement with said prongs to detachably secure the cover strip to the base strip, said base strip being of angular cross section and adapted to be fitted to a corner structure to which the fabric sheet is to extend.

11. In a mounting means for holding in place a covering sheet of fabric, a base strip adapted to be mounted on a structure to which such a sheet is to be applied, prongs formed on said strip overlying one face thereof and facing inwardly so that an edge portion of the covering sheet may be hooked thereto to overlie said strip, a cover strip of greater width than said base strip, and fastening means embodied in said cover strip on the inner side and inwardly spaced from the side edges thereof for interlocking engagement with said prongs to detachably secure the cover strip to the base strip, said base strip being of angular cross section and adapted to be fitted to a corner structure from which the fabric sheet is to extend, said cover strip being curved in cross section and having its concave surface outermost when the cover strip is secured to the base strip.

12. In a mounting means for holding in place a covering sheet of fabric, a base strip adapted to be mounted on a structure to which such a sheet is to be applied, prongs formed on said strip overlying one face thereof and facing inwardly so that an edge portion of the covering sheet may be hooked thereto to overlie said strip, a cover strip of greater width than said base strip,

and fastening means embodied in said cover strip on the inner side and inwardly spaced from the side edges thereof for interlocking engagement with said prongs to detachably secure the cover strip to the base strip, said base strip being of angular cross section and adapted to be fitted to a corner structure to which the fabric sheet is to extend, said cover strip being curved in cross section and having its convex side outermost when secured to said base strip.

13. In a mounting means for holding in place a covering sheet of fabric, a base strip adapted to be mounted on a structure to which such a sheet is to be applied, prongs formed on said strip overlying one face thereof and facing inwardly so that an edge portion of the covering sheet may be hooked thereto to overlie said strip, a cover strip of greater width than said base strip, and fastening means embodied in said cover strip on the inner side and inwardly spaced from the side edges thereof for interlocking engagement with said prongs to detachably secure the cover strip to the base strip, said base strip being of angular cross section and adapted to be fitted to a corner structure to which the fabric sheet is to extend, said cover strip being curved in cross section and having its convex side outermost when secured to said base strip.
